UNITED STATES PATENT OFFICE.

ALEXANDER T. LOYD, OF CHICAGO, ILLINOIS.

PRINTING-PRESS.

SPECIFICATION forming part of Letters Patent No. 671,384, dated April 2, 1901.

Application filed July 20, 1900. Serial No. 24,264. (No model.)

To all whom it may concern:

Be it known that I, ALEXANDER T. LOYD, a citizen of the United States, residing at Chicago, in the county of Cook, State of Illinois, have invented certain new and useful Improvements in Printing-Presses, of which the following is a specification, reference being had therein to the accompanying drawings.

This invention relates to printing-presses, and particularly to a press adapted to clamp at regular spaced intervals a series of slugs or lines of type, so that impressions may be taken from the same, and also to automatically discharge the slugs from the clamping devices if so desired.

The invention has for its object to provide a structure particularly adapted for the printing of slips used in the collection of directory information—such, for instance, as is disclosed in my pending application, Serial No. 16,341, filed May 11, 1900. In the system there-in disclosed an impression is made from the slug or type used in printing the directory for a previous year which is intended to be corrected or verified by the canvasser in acquiring data for a subsequent directory. These slips are also provided with certain identifying characters, by which the name of the party upon the slip may be accurately found in the previous directory by reference to page, column, and line.

The present invention contemplates a structure for automatically clamping a series of slugs or lines of type in order that an impression may be made therefrom, then removing the movable clamping-jaw, and, if so desired, releasing and dropping the slugs from the clamping device.

The invention also contemplates the novel structure of parts, as hereinafter set forth, by which the several operations are accomplished through the operations of a single lever in its continued movement.

Other objects and advantages of the invention will hereinafter appear in the following description and the novel features thereof will be particularly pointed out in the appended claims.

In the drawings, Figure 1 represents a plan of the press. Fig. 2 is a longitudinal vertical section showing the slugs clamped in position. Fig. 3 is a similar view showing the discharge-

slide shift to permit the slugs to drop from the clamping device. Fig. 4 is a detail plan showing the clamping device in a closed position. Fig. 5 is a similar view with the parts in an open position. Fig. 6 is a vertical longitudinal section on the line 6 6 of Fig. 5. Fig. 7 is a horizontal longitudinal section on the line 7 7 of Fig. 2. Fig. 8 is a detail of one of the slips adapted to be printed upon this press. Fig. 9 is a similar view of the type-bars used for printing the reference characters, indicating the position of the name in the directory already printed; and Fig. 10 is a transverse section on the line 10 10 of Fig. 5.

Like letters of reference indicate like parts throughout the several figures of the drawings.

The letter A designates the bed of the press, which is provided at each side with tracks or ways A', upon which may rest the journal of a suitable impression-roll A²—such, for instance, as the blanketed roll used in proof-presses. This roll is adapted to contact with the face of the types or slugs in such relation as to obtain therefrom a proper impression, as is usual in proof-presses. At one side of the bed or frame a type-bed A³ is provided, upon which may be located and secured any desired form of type or type-bars for obtaining impressions therefrom, while at the opposite side there is located a clamping device for retaining the slugs, heretofore referred to. These clamping devices may be of any desired character; but as illustrating a very desirable form thereof I have shown the same as composed of a fixed bar or bracket B, extending across the device and constituting one jaw of the clamp, in connection with which a movable plate B' is operated to form the opposite or movable jaw between which the slug or line of type B² is clamped. The plate or jaw B' is held in clamped relation by means of a tension-spring B³, extending from the bracket B and bearing against one face of the movable plate B'. Both the bracket and plate are provided with suitable pins or projections B⁴ for retaining the opposite ends of the spring in connection with the surface upon which they bear. For the purpose of separating the jaws or members of the clamping device to permit the insertion of slugs therein the ends of the movable plate B' are

provided with pintles B^5 , which extend into a recess formed in a bar C , which extends longitudinally of the series of clamping devices. This actuating-bar has between its 5 recesses projections or lugs C' , with one wall of which the pintles B^5 engage, so that when the bar is moved in the direction of the arrow in Fig. 6 the clamping-plate will be withdrawn from the fixed bracket, which permits 10 the slug or type to be removed. It will be seen that the series of clamps are all similar in construction and the movement of the plates or jaws B' is simultaneously effected throughout the series by reason of the actuating-bar C , which extends longitudinally thereof. While this bar C may be shifted by any desired means, the preferred method of accomplishing the same is herein illustrated and consists of the slotted head D , at the opposite sides of which the bars C for controlling the clamps are secured by any desired means—for instance, screws D' . The operating-slot in said head is formed with a substantially straight portion D^2 , which merges 25 at one end into a curved portion D^3 , the arc of which is that traversed by the operating roller or pin E' upon the lever E . When this roller is traversing the straight portion of the slot, it will be seen that movable jaws B' will 30 be drawn away from the fixed brackets B as the head is moved outward from the pivotal point E^2 of the lever E , while the continued movement of the lever does not affect this head D , as the slot therein is upon the arc described by the pin or roller E' . The head D is also provided with a suitable aperture D^4 , by means of which access may be obtained to the pivot E^2 whenever desired and movement of the head permitted. 35

40 The parts hereinbefore described may be secured in position by any desired means—for instance, such as will be hereinafter described in connection with other features of the invention—and the clamping-jaws provide boxes within which a series of slugs or lines of type may be held at fixed intervals apart for obtaining an impression therefrom, after which the springs B^3 may be placed under tension and the movable jaw B' withdrawn from the slug by moving the lever E into the position shown in Fig. 5, which permits the slug or type to be removed, if it be desired to preserve the same. If, however, the slug is not to be further used or is to be 45 sorted or distributed in some other manner, the same may be automatically dropped from the clamping-jaws by means of the sliding bottom beneath the boxes formed by the jaws. As illustrating a desirable form of such dropping mechanism I have provided a sliding plate F , provided with a series of apertures F' , one of which is adapted to register with each of the boxes or clamps. This plate is provided at one end with a head F^2 , provided 50 with a slot having a straight portion F^3 and a curved portion F^4 , substantially similar in outline to those in the head D , which is su-

perposed upon the head F^2 . In the head F^2 , however, the straight portion F^3 of the slot lies beneath the curved portion D^3 of the slot 70 in the head D , while the curved portion D^4 in the lower head lies beneath the straight portion D^2 in the upper head. The lever E , which carries the lug or pin E' upon its upper face, is provided with a similar pin or lug E^3 upon its lower face, adapted to travel in the slot of the head F^2 . The result of this arrangement is that when one of the plates is in movement the other remains substantially stationary, in consequence of which 75 when the jaws of the clamp-boxes have been opened a continued movement of the lever E toward the left in Fig. 5 will shift the plate F toward the fixed brackets or walls B of the boxes, as shown by dotted lines in Fig. 5, and 80 bring the apertures F' of the plate beneath the boxes, so that any slug or type contained in the boxes will drop downward therefrom and through suitable openings A^5 , formed in the bed A , upon which the boxes are usually 85 supported. They may be received in any suitable receptacle placed beneath the apertures. The plate F , between its slotted portion and its head F^2 , is provided with a suitable recess F^5 , through which the pivot-pin 90 E^2 of the lever E extends and which permits movement of the plate. The plate is also secured upon the bed A by means of flanged strips G , secured to said bed in any desired manner, and provided with ribs G' , adapted 95 to extend over the plate F at each side in order to hold and guide the same. Upon the upper face of these ribs the projections B^5 from the movable jaws, B' of the box ride and are secured in position, together with the 100 actuating-bar C , by means of a removable plate G^2 , secured to the upper portion of the strip G and overlapping a flange G^3 , extending from the strip C . It will thus be seen that the entire set of boxes is removably held upon the bed of the press and that by removal of the plate G^2 the actuating-bar C and the movable jaws B' may be removed or replaced whenever desired. 105

While the general operation of the several parts of this invention will be clearly understood from the foregoing description of its construction, still it is desirable to fully set forth the operation of the invention, particularly in connection with the printing of the 110 directory-slips, as hereinbefore referred to. As stated in the preamble, the slips to be verified by the directory canvassers are to be provided with a name appearing in a previous directory upon one portion and upon another portion with the reference characters 115 indicating the position of this name in the directory of a former year. The end of such a slip containing the reference characters is shown in Fig. 8 and in Fig. 9 the type-bars 120 by which the reference characters are imprinted and which are adapted to be supported upon the type-bed A^3 of the press. The slugs or type from which the previous directory was 125 130

printed containing the name and address of a person are clamped in the boxes, so that any desired number may be printed at once and in the same order in which they appeared in the former directory. Adjacent to these boxes and upon the bed A³ there are arranged in proper order first a type-bar H, containing a series of initial letters corresponding with each of the boxes. This bar also contains an indicating line or dash to guide in the separation of the slips into the form shown in Fig. 8 after they have been imprinted upon a sheet. Adjacent to the bar H is a series of bars H², containing numerals to indicate the directory-page, and these are so arranged in combinations as to print the desired page-number throughout the series of slugs carried in the boxes. An additional numeral-type bar H³ for indicating the columns is then inserted, and finally a line-bar H⁴, containing consecutive numerals to indicate the line in the column in which the name imprinted appears. When these several bars are prepared and secured upon the bed A³, the desired number of impressions is taken therefrom and each contains the printed line of a previous directory, together with the reference characters as to its position therein, the slugs being at this time clamped in position, as shown in Figs. 2 and 4. If the slugs are to be saved for future use, the lever E is moved to the position shown in Fig. 5, which opens the boxes and permits the slugs to be removed therefrom, while if these slugs are to be automatically discharged from the press the stop-pin I, which is inserted through the slots in the heads D and F², is withdrawn and the lever thrown to the position shown by dotted lines in Fig. 5, which presents the slots in the plate F beneath the boxes, as shown in Figs. 3 and 6, permitting the slugs to drop into a suitable receptacle.

While the invention has been described in connection with printing slips for directory uses, still it is obvious that it might be applied to the purpose of printing address-slips or for any other desired purpose to which it may be adapted. It will also be apparent that changes may be made in the details of construction and configuration without departing from the spirit of the invention as defined by the appended claims.

Having described my invention, what I claim as new, and desire to secure by Letters Patent, is—

1. A printing-press comprising a series of boxes each having a fixed jaw and a movable jaw, and means for simultaneously operating said movable jaws in one direction; substantially as specified.

2. A printing-press comprising a series of boxes each having a fixed and a movable jaw, means for simultaneously operating said movable jaws in one direction, and springs for moving said jaws into clamping relation; substantially as specified.

3. In a printing-press, the combination with

a type-bed, of a series of independent clamping-jaws spaced from each other and extending longitudinally of said bed at one side thereof; substantially as specified.

4. In a printing-press, the combination with a type-bed, of a series of clamping-jaws spaced from each other and extending parallel with said bed, and means for simultaneously opening and closing said jaws; substantially as specified.

5. In a printing-press, the combination with a type-bed, of a series of clamping-jaws spaced from each other and extending parallel with said bed, means for simultaneously opening and closing said jaws, and means for automatically discharging material clamped by said jaws; substantially as specified.

6. In a printing-press, a clamping-box comprising a fixed jaw, a reciprocating head, a jaw movable independently from said head, and an actuating-bar extending from said head and adapted to engage a projection from said jaw to move the same in one direction; substantially as specified.

7. In a printing-press, a clamping-box comprising a fixed jaw, a reciprocating head, a jaw movable independently from said head, an actuating-bar extending from said head and adapted to engage a projection from said jaw to move the same in one direction, and a spring extending from a fixed part and bearing against said movable jaw; substantially as specified.

8. In a printing-press, a clamping-box comprising a fixed jaw and a movable jaw having a projection, a reciprocating head, an actuating-bar extending from said head and adapted to engage the projection from said jaw, a spring extending from a fixed part and bearing against said movable jaw; and an operating-lever having a pin or lug adapted to operate in a slot in said head for reciprocating the same; substantially as specified.

9. In a printing-press, a box comprising a fixed jaw and a movable jaw, an actuating-bar for said movable jaw, a head carried at one end of said bar and provided with a slot having a straight and a curved portion, and a pivoted operating-lever provided with a pin traveling in said slot; substantially as specified.

10. In a printing-press, a box comprising a fixed jaw and a movable jaw, an actuating-bar for said movable jaw, a head carried at one end of said bar and provided with a slot having a straight and a curved portion, a pivoted operating-lever provided with a pin traveling in said slot; a slotted plate adapted to slide beneath said boxes, a head upon said plate provided with a slot having a straight and a curved path, and a projection from said lever adapted to travel in said slot; substantially as specified.

11. In a printing-press, the combination with an apertured bed, of a slotted plate adapted to slide upon the same, a series of clamping-boxes above said plate, means for

- opening and closing said boxes, and means for shifting said plate to bring the apertures therein into register with said boxes and the apertured bed; substantially as specified.
12. In a printing-press, the combination with an apertured bed, of a slotted plate adapted to slide upon the same, a series of clamping-boxes above said plate, means for opening and closing said boxes, means for shifting said plate to bring the apertures therein into register with said boxes and the apertured bed, and an operating-lever adapted in its continued movement to open said boxes and to shift the apertures in said plate into alinement with the open boxes; substantially as specified.
13. In a printing-press, a bed having at one side thereof means for holding a slug or type, and means adapted to be secured to said bed for printing reference characters opposite said slug; substantially as specified.
14. In a printing-press, a box composed of a fixed jaw and a movable jaw having projections at opposite ends, an actuating-bar having lugs adapted to engage said projections, a head carried at one end of said bar, and means for reciprocating said head; substantially as specified.
15. In a printing-press, a box composed of a fixed jaw and a movable jaw having projections at opposite ends, an actuating-bar having lugs adapted to engage said projections, a head carried at one end of said bar, means for reciprocating said head, a slotted plate beneath said boxes, a head upon said plate, and means for reciprocating said plate and head while the head of the actuating-bars is held in one position; substantially as specified.
16. In a printing-press, a box composed of a fixed jaw and a movable jaw having projections at opposite ends, an actuating-bar having lugs adapted to engage said projections, a head carried at one end of said bar, means for reciprocating said head, a slotted plate beneath said boxes, a head upon said plate, means for reciprocating said plate and head while the head of the actuating-bars is held in one position; a strip upon said bed having a rib extending over the edge of said slotted plate, and a holding-plate adapted to retain the projection from the movable jaw and the actuating-bar in position upon the upper surface of said rib; substantially as specified.
17. In a printing-press, a box composed of a fixed and a movable jaw, an actuating-head adapted to move said jaw and provided with a slot therein, a sliding apertured plate beneath said boxes, a slotted head provided upon said plate, a pivoted actuating-lever extending between said heads and provided with projections extending into the slots of each plate; substantially as specified.
18. In a printing-press, a box composed of a fixed and a movable jaw, an actuating-head adapted to move said jaw and provided with a slot therein, a sliding apertured plate beneath said boxes, a slotted head provided upon said plate, a pivoted actuating-lever extending between said heads and provided with projections extending into the slots of each plate, and a stop-pin adapted to extend into the path of the pivoted lever to limit the movement of said lever; substantially as specified.
19. In a printing-press, the combination with an apertured bed, clamping-boxes located above the same, an apertured sliding plate between said boxes and bed, an operating-lever adapted to successively open said boxes and shift said plate, and removable means to limit the movement of said lever and prevent the shifting of said plate; substantially as specified.
20. In a printing-press, an apertured bed, a clamping-box above the same, a slotted plate between said bed and box provided with an operating-head having a slot with a straight and a curved path, a head for opening said box provided with a straight and a curved portion disposed in an opposite direction to those of the slot in the apertured plate, and an operating-lever provided with projections traveling in said slots; substantially as specified.

In testimony whereof I affix my signature in presence of two witnesses.

ALEXANDER T. LOYD.
